Primary Examiner — John Windmuller(74) *Attorney, Agent, or Firm* — Knobbe, Martens, Olson & Bear, LLP; Kevin J. Everett(57) **CLAIM**

The ornamental design for a vehicle antenna module, as shown and described.

DESCRIPTION

FIG. 1 is a perspective top left view of a vehicle antenna module according to the present invention;
 FIG. 2 is a front elevational view thereof;
 FIG. 3 is a rear elevational view thereof;
 FIG. 4 is a left side elevational view thereof;
 FIG. 5 is a right elevational view thereof;
 FIG. 6 is a top plan view thereof; and,
 FIG. 7 is a left side elevational view showing the vehicle antenna module in use, mounted on a roof of a vehicle.
 The broken lines shown in FIG. 7 illustrate environmental subject matter only, such as a roof of a vehicle, and form no part of the claimed design.
